UNITED STATES PATENT OFFICE.

MAX SPILLMAN, OF RICHFIELD, NEW JERSEY, ASSIGNOR TO WORTHINGTON PUMP AND MACHINERY CORPORATION, OF NEW YORK, N. Y., A CORPORATION OF VIRGINIA.

CENTRIFUGAL PUMP.

Application filed January 18, 1922. Serial No. 530,074.

To all whom it may concern:

Be it known that I, MAX SPILLMAN, a citizen of Switzerland, residing at Richfield, county of Passaic, and State of New Jersey, have invented certain new and useful Improvements in Centrifugal Pumps, fully described and represented in the following specification and the accompanying drawings, forming a part of the same.

10 This invention relates to improvements in centrifugal pumps.

The chief object of the invention is to provide a cheap, compact and highly efficient multistage centrifugal pump of light weight and little subject to wear. The pump is especially adapted for use as a mine pump, in which low weight is an important factor, especially when the pump is made of bronze, and in which the reduction of 15 wearing effect from the liquid, due to the shape of the passages and strong design of the parts subject to wear, is vital because of the wearing action of mine water.

For a full understanding of the invention, a full description of a construction embodying all the features of the same in their preferred form will now be given in connection with the accompanying drawings forming a part of this specification, and the features forming the invention then specifically pointed out in the claims.

In the drawings—

Fig. 1 is a longitudinal section of a pump of the preferred form;

35 Figs. 2 and 3 are, respectively, sections on the lines 2—2, 3—3 of Fig. 1.

Referring now to the drawings; the pump comprises a shaft 10 upon which are mounted suitable impellers 11, four impellers of the closed type being shown in the present instance, separated by suitable partition members 12 and enclosed by a pump casing A, preferably made in two parts consisting of a lower section 13 and an upper section 14, the lower section 13 preferably carrying the inlet and outlet connections 17, 18. The pump shaft 10 is provided at opposite ends with suitable bearings 15 and the usual stuffing boxes 16. Each impeller 11, except 40 the last, discharges through a plurality of passages between the dividing fins 1 and the outer casing, three such passages a, b, c preferably being provided, as shown. These discharge passages gradually expand

55 radially from the impeller so as to convert the velocity of the pumped liquid into pressure, and deliver at right angles through the outlets a', b', c', to corresponding chambers a'', b'', c'', from which the liquid passes inwardly through an annular passage d 60 formed in the partition 12 and shown as divided by the usual vanes 2, to the eye of the next impeller, this construction being repeated through the successive impellers to the last impeller 11. The openings a', b', c' 65 through which the liquid passes sideways, and the chambers a'', b'', c'', are preferably formed as shown, so as to diminish in radial dimensions from the passages a, b, c on a suitable curve, the form of casing resulting therefrom eliminating stresses which would result from an abrupt change 70 of flow in the chambers and improving the appearance of the pump. The impeller of the last stage, the fourth in the construction 75 shown, may deliver to any suitable form of discharge, but preferably delivers to the well-known single volute discharge chamber 3, the latter developing into the discharge connection 18.

80 The casing A is not circular or volute in form, except that it may be circular or volute for the last stage with its single volute, but is shaped to conform to the plurality of delivery passages surrounding 85 the impellers, and in the preferred three-delivery construction shown, is of a form generally that of an equilateral triangle, with one side of the triangle forming the horizontal base of the pump, and two of the 90 deliveries for each impeller being formed in this base section 13 of the casing and one in the upper section 14 at the top of the casing. This form is best adapted for the support of the pump, and with the divided 95 casing produces a structure that is very simple of manufacture and has great strength to resist the pump stresses without great weight of material. Leakage between the stages is reduced, also, as compared with 100 a pump of equal capacity having a circular casing and especially with diffusing rings, the casing joints in the present construction being much nearer the center so that the strain on the joint and tendency to open 105 up the joint on the inside are less. While this three-delivery and generally triangular form of pump casing is preferred, however,

and in itself forms an important part of the invention, it will be understood that the broader features of the invention may be may be embodied in constructions having a different number of delivery passages for the impellers and a casing of other than generally triangular form.

It will be understood that the invention is not limited to the special type or number 10 of impellers shown nor to the detailed construction of the casing or pump parts, but that modifications may be made therein while retaining the invention defined by the claims.

15 What is claimed is:

1. A centrifugal pump having three delivery passages surrounding the impeller and formed between dividing fins and the pump casing, said delivery passages increasing in 20 radial dimensions from the impeller to the discharge openings through which the liquid passes sidewise through the passage wall, chambers at the side of the passages receiving the discharge and decreasing in 25 radial dimensions from said discharge openings, and an outside casing surrounding the delivery passages and chambers and having generally the form of an equilateral triangle with one of said discharge openings 30 at each angle.

2. A centrifugal pump having three delivery passages surrounding the impeller and formed between dividing fins and the pump casing, said delivery passages increasing in 35 radial dimensions from the impeller to the discharge openings through which the liquid passes sidewise through the passage wall, chambers at the side of the passages receiving the discharge and decreasing in radial 40 dimensions from said discharge openings, and an outside casing surrounding the delivery passages and chambers and having generally the form of an equilateral triangle with one of said discharge openings 45 at each angle and one side of the triangle forming the horizontal base of the pump.

3. A centrifugal pump having three delivery passages surrounding the impeller and formed between dividing fins and the 50 pump casing, said delivery passages increasing in radial dimensions from the impeller to the discharge opening through which the liquid passes sidewise through the passage wall, chambers at the side of the passages 55 receiving the discharge and decreasing in radial dimensions from said discharge openings, and an outside casing surrounding the delivery passages and chambers and having generally the form of an equilateral triangle 60 with one of said discharge openings at each angle and one side of the triangle forming the horizontal base of the pump, said pump casing being divided horizontally with two of the dividing fins and delivery passages 65 and openings formed in the lower section.

4. A multistage centrifugal pump having a plurality of impellers arranged in series with three delivery passages surrounding each impeller and formed between dividing fins and the pump casing, said delivery passages increasing in radial dimensions from the impellers to discharge openings through which the liquid passes sidewise through the passage wall, chambers for each impeller at the sides of the passages receiving the discharge and decreasing in radial dimensions from said delivery openings, said chambers extending to and connecting with the inlet of the next impeller, and a pump casing surrounding the discharge passages and chambers and conforming in outside shape thereto and having generally the form of an equilateral triangle with one of said discharge openings at each angle.

5. A multistage centrifugal pump having a plurality of impellers arranged in series with three delivery passages surrounding each impeller and formed between dividing fins and the pump casing, said delivery passages increasing in radial dimensions from the impellers to discharge openings through which the liquid passes sidewise through the passage wall, chambers for each impeller at the sides of the passages receiving the discharge and decreasing in radial dimensions from said delivery openings, said chambers extending to and connecting with the inlet of the next impeller, and a pump casing surrounding the discharge passages and chambers and conforming in outside shape thereto and having generally the form of an equilateral triangle with one of said discharge openings at each angle and one side of the triangle forming the horizontal base of the pump.

6. A multistage centrifugal pump having a plurality of impellers arranged in series with three delivery passages surrounding each impeller and formed between dividing fins and the pump casing, said delivery passages increasing in radial dimensions from the impellers to discharge openings through which the liquid passes sidewise through the passage wall, chambers for each impeller at the sides of the passages receiving the discharge and decreasing in radial dimensions from said delivery openings, said chambers extending to and connecting with the inlet of the next impeller, and a pump casing surrounding the discharge passages and chambers and conforming in outside shape thereto and having generally the form of an equilateral triangle with one of said discharge openings at each angle and one side of the triangle forming the horizontal base of the pump, said pump casing being divided horizontally with two of the dividing fins and delivery passages and openings formed in the lower section.

7. A centrifugal pump having a plurality

of delivery passages surrounding the impeller and formed between dividing fins and the pump casing, said delivery passages increasing in radial dimensions from the impeller to discharge openings through which the liquid passes sidewise through the passage wall, chambers at the side of the passages receiving the discharge and decreasing in radial dimensions from said discharge openings, and a pump casing surrounding said delivery passages and chambers, said casing having increasing and decreasing outside radial dimensions corresponding to the increase and decrease in radial dimensions of the delivery passages and chambers and with one of said discharge openings at each point of greatest radius.

In testimony whereof, I have hereunto set my hand.

MAX SPILLMAN.
